UNITED STATES PATENT OFFICE.

CORA G. BEESLEY, OF CHICAGO, ILLINOIS.

MARCEL WAVER.

Application filed July 18, 1924. Serial No. 726,656.

This invention relates to improvements in Marcel wavers and one of the objects of the invention is to provide an improved device of this character by means of the use of which a Marcel wave may be readily and effectively given to the hair.

Heretofore with the use of hand irons as now constructed it has been necessary to twist or turn the iron so as to procure in the hair the necessary arrangement of the curves or waves, with the result that it is difficult to manage the hair and manipulate the iron and at the same time prevent pulling of the hair and burning of the scalp.

It is one of the objects of the present invention to overcome these difficulties and objections and to provide an improved hand iron of this character which will be of a simple, durable, and comparatively cheap construction which will be effective and efficient in operation, and with which iron there is associated means for positioning and holding the hair while the irons are being placed in position; the parts being so arranged that there will be no projection to contact with head of the person whose hair is being treated.

To the attainment of these ends the accomplishment of other new and useful objects as will appear, the invention consists in the features of novelty in substantially the construction, combination and arrangement of the several parts hereinafter more fully described and claimed and shown in the accompanying drawings illustrating the invention, and in which drawings:

Figure 1 is a view partly in elevation, partly in longitudinal section and partly broken away of a device of this character constructed in accordance with the principles of this invention.

Figure 2 is a top plan view of Figure 1.

Figure 3 is a sectional view taken on line 3-3 Figure 2.

Figure 4 is a sectional view taken on line 4-4 Figure 1.

Figure 5 is a right hand end elevation of Figure 1, with parts omitted.

Figure 6 is a longitudinal sectional view taken on line 6-6 Figure 2.

Referring more particularly to the drawings the numeral 10 designates a support of any desired size and configuration and

constructed of any suitable material. To the support 10 and preferably adjacent one end 55 thereof, is connected a handle 11 by means of which the device may be transported. Pivotedly mounted upon the base 10 are a plurality of irons 12, which may be of the ordinary and well known construction, the 60 specific construction of the body of which constitutes no part of the present invention, suffice it to say that the irons 12 are of the usual electric type and are adapted to be heated by means of current supplied thereto 65 through suitable conductors 13, to these conductors 13 is connected another conductor 15 the latter being adapted to be attached to the usual source of supply of electricity or current, such as by means of the well 70 known plug and socket connection. The conductor 15 preferably passes through the handle 11 and the conductors 13 preferably pass through a tubular bearing 16 supported preferably adjacent the handle end of the 75 base or support 10 and extends transversely of the base.

Each of the irons 12 is mounted upon the base or support 10 for pivotal movement with respect thereto and independently with 80 respect to each other. To that end each of the irons may be provided at one end with a tubular bearing 17 which is sleeved over the tubular bearing 16 and the respective bearings 17 of adjacent irons 12 are held 85 laterally spaced from each other in any suitable manner such as by means of spacing members or sleeves 18.

The extremity of each of the irons 12, which is connected with the bearing 16 is 90 preferably tubular as at 19, and the bearing 16 is provided with a plurality of elongated openings 20 individual to the irons, and with which openings 20 the tubular ends 19 of the respective irons 12 register. The 95 conductors 13 pass through the respective openings 20 and into the respective tubular ends 19 of the irons so that the irons may be readily moved about their points of pivotal connections with the bearing 16 without 100 injuring the conductors 13.

The irons may be of any desired size and length and each is preferably provided at its free end with a suitable handle 21 by means of the use of which handle the irons 105 may be readily moved about their pivots.

The pivots of the irons are preferably disposed in close proximity to the base or support 10 so that when the free ends of the irons are moved to points adjacent the base 5 or support 10, the irons will stand in close proximity to the base and substantially parallel thereto.

If desired suitable heat insulating material 22 may be provided between the base 10 or support 10 and the irons so as to prevent injury to the scalp in the event that the irons become overheated.

Any suitable means may be provided for 15 yieldingly locking the irons 12 in an operative position with respect to the base and support 10, or in the position shown in full lines in Figure 1. To that end there may be provided an enlargement or shoulder portion 23 disposed adjacent the free end of 20 the irons and preferably in proximity to the handle 21. These portions 23 are adapted to engage yieldable catch devices 24, the stress of which is sufficient to retain the irons when pressed down upon the 25 hair and thereby maintain the irons in proper position during the formation of the waves, but will yield under abnormal stress to permit the irons to be swung about their pivots by the handles 21.

Any suitable means may be provided for 30 maintaining the irons in elevated position with respect to the base or support 10, to permit of the arrangement of the hair upon the device before the irons are brought into 35 contact with the hair.

A suitable and efficient means for accomplishing this end embodies a spring like device or formation 25 which is arranged 40 adjacent the pivot of the iron 12 and co-operates with a flat surface 26 on the bearing 17 of the iron. When the iron is lowered to the position shown in full lines in Figure 1, the flat surface will pass out of engagement to the spring 25, the latter yielding sufficiently to permit this movement. When, however, the iron is raised to the 45 dotted line position in Figure 1 the flat surface 26 will contact with the spring 25 and the iron will be yieldingly held in its raised 50 position.

Co-operating with the irons are a plurality of comb like devices 27 which may be constructed of any suitable material and may be of any desired size and length. 55 These comb-like devices are arranged alternately with the irons 12 and are parallel thereto, the teeth of the comb-like devices projecting for any desired distance above the base or support 10 and for any desired 60 distance above the irons when the latter are in the position shown in Figures 1 and 4. It is, however, preferable that the base of the teeth of the combs shall terminate in a plane below the plane of the top surface of the iron. The comb like devices

are mounted for bodily longitudinal shafting movements with respect to the base or support 10 and in directions lengthwise of the comb-like devices and also lengthwise of the irons 12.

Any suitable means may be provided for so mounting the comb-like devices such for instance as guides 28 (see Figure 4) which house the base of the comb like devices and these guides are provided with an elongated slot 29 (see Figure 2), the slot being somewhat longer than the length of the comb so as to permit the comb to be longitudinally shifted.

The combs are preferably shifted by 60 means of a suitable handle 30 connected therewith, and the combs may be held in their adjusted positions in any suitable manner, preferably by means of suitable teeth or projections 31 on the body of the 65 comb, and which teeth or projections are adapted to pass over and co-operate with another tooth or projection 32 connected with the base or support 10. The teeth 31 are preferably arranged so as to point in 70 one direction thereby enabling the operator to ratchet the teeth 31 over the tooth 32 when the comb is moved one direction. The portion 33 of the comb on which the teeth 31 are located is preferably slightly yieldable so as to permit of the adjustment of 75 the comb. When it is desired to move the comb in the opposite direction the teeth 31 may be elevated with respect to the tooth 32 so as to pass over the latter.

In operation the hair is first combed in the usual manner.

The irons 12 are then elevated with respect to the base or support to the dotted line position in Figure 1. The comb like devices 27 are then adjusted longitudinally of the base or support 10 so that the combs will stand in alinement with each other and at any desired position with respect to the 105 length of the respective slots but preferably in the center of the slots 29. The hair is then laid across all of the comb like devices 27 and between the teeth thereof. The first iron 12 is then lowered into contact with the hair and fastened in its lower position by 110 means of the catch formation 24-23. The second comb-like device 27 is then shifted longitudinally in the slot 29, while in engagement with the hair and with respect to the first comb like device so as to deflect or 115 bend the hair transversely thereof and in a direction lengthwise of the iron. The comb that has just been adjusted will be held in its position by the catch devices 31-32.

The second iron 12 is then lowered and secured in position. The second comb like device is then moved back to its original position. The third comb like device may then be shifted in its slot and with respect to the second comb. The third iron 12 is then low-

ered and fastened. The third comb like device 27 may then be again shifted in its slot and with respect to the second comb like device, after which the fourth iron may then 5 be lowered and secured in position.

Obviously, the comb like devices and irons may be relatively adjusted one with respect to the other in any desired or suitable manner according to the shape of the wave 10 in the hair that it is desired to produce.

It will be noted that the guides 28 intermediate the comb like devices 27 are shaped as at 34 (see Figure 4) to form cradles or 15 pockets into which the irons 12 press the hair when in engagement therewith and as these pockets 34 are preferably of a rounding or semi-circular configuration, a similar shape will be given to the hair.

After the irons have been allowed to remain in contact with the hair for the necessary or desired length of time, they may be 20 released and elevated by grasping the handles 21. During the operation of this device it is to be understood that the operator holds the same with one hand by the handle 25 11. This will leave the other hand free to manipulate the hair and operate the irons and comb like devices.

With this improved construction it will 30 be manifest that it is not necessary to twist or turn the entire device and there will be given to the hair two distinct waves, that is to say, two different waves will be formed in the hair in planes intersecting each other.

While the preferred form of the invention 35 has been herein shown and described, it is to be understood that various changes may be made in the details of construction and in the combination and arrangement of the various parts, within the scope of the claims, 40 without departing from the spirit of this invention.

What is claimed as new is:

1. A Marcel waver including an iron, 45 means for heating the iron, a comb like device co-operating with the iron, means connecting the iron adjacent one end and the said comb like device for pivotal movement one with relation to the other, means mounting the comb like device for bodily adjustment in directions lengthwise of the iron and within the confines of the ends of the iron, and means for locking the iron and the said comb like device against relative pivotal 50 movement, the last recited means including a yielding catch like formation co-operating with the free end of the said iron.

2. A Marcel waver including a support, a 55 handle connected therewith, an iron pivotally connected adjacent one end with the support for movement toward and away from the support, a comb like device connected with the support for bodily movement with respect thereto and with respect 60 to the said iron and within the confines of

the ends of the iron, means for heating the iron, said comb like device being substantially parallel with the iron when the latter is in a position substantially parallel with the said support, means for bodily adjusting 70 the said comb like device with respect to the said iron, and means for yieldingly locking the said iron in proximity to the said support.

3. A Marcel waver including a support, a 75 handle connected therewith, an iron pivotally connected adjacent one end to the support, means for yieldingly locking the free end of the iron adjacent the support, a comb like device connected with the support for 80 bodily lengthwise adjustment with respect to the support and the said iron, and means for maintaining the said comb like device in its adjusted position.

4. A Marcel waver including a support, a 85 handle connected therewith, an iron pivotally connected adjacent one end to the support, means for yieldingly locking the free end of the iron adjacent the support, a comb like device connected with the support for 90 bodily lengthwise adjustment with respect to the support and the said iron, means for maintaining the comb like device in its adjusted position, and means for yieldingly maintaining the said iron in an elevated 95 position with respect to the said support.

5. A Marcel waver including a support, a handle connected therewith, an iron pivotally connected adjacent one end to the support, means for yieldingly locking the 100 free end of the iron adjacent the support, a comb like device connected with the support for bodily lengthwise adjustment with respect to the support and the said iron, means for maintaining the said comb 105 like device in its adjusted position, and means for heating the said iron.

6. A Marcel waver including a support, a plurality of laterally spaced irons pivotally connected with the support, said irons being substantially parallel when their bodies are in proximity to the support, means individual to the irons for yieldingly locking their free ends adjacent the support, and comb like devices interposed between 110 adjacent irons, said comb like devices being mounted for bodily adjustment one with respect to the other and in directions lengthwise of each other.

7. A Marcel waver including a support, a 115 plurality of laterally spaced irons pivotally connected with the support, said irons being substantially parallel when their bodies are in proximity to the support, means individual to the irons for yieldingly locking their 120 free ends adjacent the said support, comb like devices interposed between adjacent irons, said comb like devices being mounted for bodily adjustment one with respect to the other and in directions lengthwise of 125 130

each other, and means for maintaining the said comb like devices in their adjusted positions with respect to each other.

8. A Marcel waver including a support, a plurality of laterally spaced irons pivotally connected with the support, said irons being substantially parallel when their bodies are in proximity to the support, means individual to the irons for yieldingly locking their free ends adjacent the said support, comb like devices interposed between adjacent irons, said comb like devices being mounted for bodily adjustment one with respect to the other and in directions lengthwise of each other, means for yieldingly maintaining the said comb like devices in their adjusted positions with respect to each other, and means for yieldingly maintaining the said irons in their elevated positions about their pivots.

9. A Marcel waver including a support, a handle therefor, a plurality of irons independent of each other and pivotally connected adjacent one of their respective ends with the support, means for heating the irons, spaced parallel comb like devices connected with the support for bodily movement with respect thereto, said comb like devices being alternately arranged with the said irons and being substantially parallel thereto when the irons are in position adjacent the said support, and means for bodily adjusting the said comb like devices in lengthwise directions and in directions lengthwise of the said irons.

10. A Marcel waver including a support, a handle therefor, a plurality of irons independent of each other and pivotally connected adjacent one of their respective ends with the support, means for heating the irons, spaced parallel comb like devices connected with the support for bodily movement with respect thereto, said comb like devices being alternately arranged with the said irons and being substantially parallel thereto when the irons are in position adjacent the said support, means for bodily adjusting the said comb like devices in lengthwise directions and in directions lengthwise of the said irons, and means individual to the said irons for yieldingly locking their free ends adjacent the said support.

11. A Marcel waver including a support, a handle therefor, a plurality of irons independent of each other and pivotally connected adjacent one of their respective ends with the support, means for heating the irons, spaced parallel comb like devices connected with the support for bodily movement with respect thereto, said comb like devices being alternately arranged with the said irons and being substantially parallel thereto when the irons are in position adjacent the said support, means for bodily adjusting the said comb like devices in

lengthwise directions and in directions lengthwise of the irons, means individual to the said irons for yieldingly locking their free ends adjacent the said support, and means for yieldingly maintaining the free ends of the said irons elevated with respect to the said support.

12. A Marcel waver including a plurality of alternately arranged and substantially parallel comb like devices and irons, means for heating the irons, and means pivotally connecting the said comb like devices and the said irons adjacent one end for movement about said pivot one with respect to the other in directions one toward and away from the other, and means mounting the comb like devices for relative longitudinal movement one with relation to the other and independently of and with respect to the movement of the irons.

13. A Marcel waver including a plurality of alternately arranged and substantially parallel comb like devices and irons, means for heating the irons, means mounting the comb like devices for relative longitudinal movement one with relation to the other, means pivotally connecting the said comb like devices and the said irons adjacent one end for movement about said pivot one with respect to the other in directions one toward and away from the other, and means for yieldingly locking the parts against movement about their pivots.

14. A Marcel waver including a plurality of alternately arranged and substantially parallel comb like devices and irons, means for heating the irons, means mounting the comb like devices for relative longitudinal movement one with relation to the other, means pivotally connecting the said comb like devices and the said irons adjacent one end for movement about said pivot one with respect to the other in directions one toward and away from the other, means for yieldingly maintaining the free ends of the respective irons and comb like devices separated, and means for yieldingly locking the free ends of the parts in close proximity.

15. A Marcel waver including an iron, a comb like device co-operating therewith, means for heating the iron, means connecting the iron and comb like device in a manner that one end thereof may be moved toward and away from the other, means mounting the said comb like device for longitudinal adjustment with respect to the said iron and within the confines of the ends of the iron, and means for yieldingly locking the free ends of the said parts in close proximity to each other.

16. A Marcel waver including an iron, a comb like device co-operating therewith, means for heating the iron, means connecting the iron and the comb like device in a

manner that one end thereof may be moved toward and away from the other, means mounting the said comb like device for longitudinal adjustment with respect to the 5 said iron and within the confines of the ends of the iron, and means for yieldingly maintaining the said iron in a separated position with respect to the said comb like device.

10 17. A marcel waver including a plurality of irons, a plurality of comb like devices cooperating therewith, means pivotally mounting the irons with respect to the comb

like devices, means mounting the comb like devices for bodily adjustment with 15 respect to and in directions lengthwise of the irons, means yieldingly locking the said irons and comb like devices against a separating movement about the said pivot, and means for yieldingly maintaining the 20 said irons and comb like devices in their separated positions.

In testimony whereof I have signed my name to this specification, on this 15th day of July, A. D. 1924.

CORA G. BEESLEY.
